239,933

ELECTRIC TIMES TABLE TEACHING INSTRUMENT

James F. Champaigne, 1011 Golfview Lane,
South Bend, Ind. 46614

Filed Aug. 22, 1974, Ser. No. 499,517

Term of patent 14 years

Int. Cl. D19—07

U.S. Cl. D19—60

Fig. 1

Fig. 2

Fig. 3

Fig. 4

Fig. 5

Fig. 6

FIG. 1 is a perspective view of an electric times table teaching instrument embodying the present design;

FIG. 2 is an elevational view of the side opposite that shown in FIG. 1;

FIG. 3 is a rear elevational view;

FIG. 4 is a top plan view;

FIG. 5 is a front elevational view; and

FIG. 6 is a bottom view.

I claim:

The ornamental design for an electric times table teaching instrument, substantially as shown.
